COIN OPERATED ELECTRIC SWITCH

Fred H. Osborne, Snyder, N. Y., assignor to The
Rudolph Wurlitzer Company, Cincinnati, Ohio,
a corporation

Application December 22, 1939, Serial No. 310,524

6 Claims. (CL 194—9)

This invention relates to a coin operated electric switch particularly adapted to the control of automatic musical instruments and the like. This application is a continuation in part of my prior application Serial No. 301,359, filed October 26, 1939.

In apparatus of this general type it is common practice to provide an electromagnetically operated register which is actuated one or more times whenever a coin is deposited in a receiving device, the number of actuations by each coin being determined by the value of the coin. Usually in coin receiving units now used for this purpose, a coin drops or rolls by gravity through a restrained path in which it actuates successively a plurality of electric switches or other means for actuating the electromagnetic register. Since the weight of a coin is relatively small, the moving parts used to actuate the switches must be correspondingly light and delicate and as free as possible from friction. The force available for making electrical contact is correspondingly small so that contact points must be maintained in perfect condition if positive contact is to be secured. The weight of coins of the same denomination vary greatly with age, so the counterweights or springs used to oppose the action of the coin must be calibrated to respond to the action of coins of different weights. Such calibration is difficult to obtain. Switches sufficiently light for gravity operation are subject to vibrations which are apt to produce multiple operation where only single operation is desired. The poor electrical conductivity inherent in such switches, on the other hand, may cause complete failure to operate, especially as the age of the switch increases, moving parts become worn and contact points become fouled. In short, a switch construction adapted for gravity operation is too light to be either durable or positive in operation.

Another difficulty encountered with gravity operated switches is the excessive time consumed in making multiple contacts with a single coin. If a quarter dollar is to make five contacts, for example, it is important that all five contacts be completed before another coin can be received. Otherwise, the first contact of the second coin may occur simultaneously with one of the contacts of the first coin and the two simultaneous contacts then produce only a single actuation of the register. In gravity operation, some of the momentum of the coin is lost at each actuation of a switch. Time must be permitted for this momentum to be regained before another switch can be operated by the same coin. The speed of a coin travelling by gravity is a variable factor contingent upon the friction encountered and other uncontrollable elements. The time spacing of multiple contacts is therefore not uniform.

One object of the present invention is to increase the energy available for operating coin controlled electric switches over that available with gravity operation. This is accomplished by 5 providing power means for operating said switches, the operation of said power means being preferably initiated by a manual operation which also delivers the coin to the apparatus. By this means the switch parts may be made much 10 heavier and more durable, springs or counterweights need not be so closely calibrated and positive operation of the desired number of contacts is insured.

Another object of the invention is to provide 15 means by which the speed of multiple operations with a single coin may be increased and the time spacing of multiple contacts may be made uniform. This is accomplished by the use of the power operated means for operating the switches 20 under control of the coins.

Another object of the invention is to prevent 25 cheating by tampering with the power supply. In a switch of this type, power for operating the coin register is most advantageously supplied from a common attachment plug inserted in the usual wall socket, and it is desirable that the power for moving the coin be obtained from the same source. Since the coin is in contact with the switch element for an appreciable length of 30 time it is possible to pull the plug during that instant, stop the travel of the coin and then reinsert the plug. Such manipulation would result in registering a false coin value unless means are provided to prevent it. In the present invention, interlocking means are provided preventing operation of the coin register after the power supply has been broken until the coin has moved sufficiently to clear a switch element with 35 which it may have been in contact when the break in power supply occurred.

Other objects and features of the invention will be understood from the accompanying drawings and the following description and claims:

Fig. 1 is a side view of a coin controlled device 45 constructed in accordance with the invention with parts omitted for sake of clearness. Fig. 2 is a side view on a larger scale of a portion of the device shown in Fig. 1 illustrating the parts in more detail. Fig. 3 is a similar view 50 of the opposite side thereof. Fig. 4 is a sectional view taken on the line 4—4 of Fig. 2. Fig. 5 is a perspective view of a detail of the apparatus. Fig. 6 is a perspective view of another detail. Fig. 7 is a fragmentary view in elevation of parts 55 shown in Fig. 2 shown in a different operating position. Fig. 8 is a diagram of electrical connections. Fig. 9 is an elevational view with parts in section, showing arrangement of parts by means of which the number of switch actuations 60 for coins of different value is determined. Fig.

10 is an elevational view showing an arrangement of parts used when a plurality of coin receiving devices are used for coins of different values.

Referring now to Fig. 1, there is illustrated a wall 10 which may be the wall of the cabinet of a phonograph or of a wall box remotely positioned from the phonograph or other unit to be controlled by the apparatus. A coin slide 11 is mounted on the wall 10 and projects outside of said wall for the receipt of coins. Said slide may be of the common commercial form which is pressed inwardly when a coin has been deposited therein and which delivers the coin to a hopper or other receiver on the inner side of the wall. In the present case the slide 11 delivers the coin to a hopper 12 of the coin controlled switch mechanism proper. In the drawings, the slide is placed sufficiently far above said hopper so that the usual ejecting mechanism for eliminating slugs or counterfeit coins may be inserted therebetween. This mechanism is omitted from the drawings for the sake of clearness since it forms no part of the invention and may be of any common commercial form. In the case of apparatus adapted to receive coins of several denominations, one of the slides 11 is furnished for each denomination and the hopper 12 is provided with suitable partitions for receiving the coins in different compartments.

The stationary body of the device proper consists of a bank of plates 13 to 21, inclusive, all secured together as a rigid structure by means of bolts 28 and 29. This structure is provided with brackets 30 and 31 by means of which it may be secured to the wall 10. A shaft 32 extends horizontally through the bank of plates 13 to 21 and carries a bushing 33 secured thereto and in turn carrying a rotor consisting of a series of discs 34 to 40, inclusive, which are held in position on the bushing 33 by means of a nut 41.

The outlines of the several plates 13 to 21, inclusive, are such as to provide constrained guideways for the coins received from the hopper 12, to guide said coins downwardly into engagement with the rotor, about a portion of the periphery of the rotor and then downwardly therefrom to a discharge point. The plates 19 and 22, the outlines of which are indicated in Fig. 3, provide the path of a 25¢ piece and guide the same into engagement with rotor plate 35. Plates 17 and 24, shaped respectively like plates 19 and 22, guide the 10¢ coins into engagement with rotor plate 31. Plates 15 and 26, similarly shaped, guide the 5¢ coin into engagement with rotor plate 35. Plate 20, the shape of which can also be determined from Fig. 3, forms a partial closure for the 25¢ path. Plates 17 and 16, shaped substantially like plate 20, provide partial partitions between the 25¢ path and the 10¢ path and between the 10¢ path and the 5¢ path respectively. Plate 23, aligned with plate 18, projects beyond the surface of plate 22 as seen in Fig. 3 and forms a more complete closure between the 25¢ and 10¢ paths. Plate 25, shaped like plate 23, performs the same function between the 10¢ and 5¢ paths. Plates 14 and 27, shaped like plates 20 and 23 respectively, form an outer restraining face for the 5¢ path. Plate 21 has the same shape as plate 22 since the size of the 25¢ coin makes it unnecessary to provide other restraining means than plate 20.

The outer diameters of the rotor discs 35, 37 and 39 are such that the coin paths between

said discs and the plates 19, 17 and 15 are slightly narrower than the diameters of the coins for which said paths are intended. Said rotor discs are preferably formed of live rubber adapted to yield sufficiently to pass the coins through said paths and to press the coins firmly against the opposing stationary plates. Slippage between the outer edges of the coins and the stationary plates is prevented thereby and the power driven movement of the rotor discs hereinafter described imparts a positively driven rolling movement to the coins throughout that part of their travel in which they are in contact with the rotor.

A switch operating lever 42 is pivotally mounted on a pivot screw 43 secured to the plate 20 and is provided with fingers 44 and 45 inwardly turned and projecting through suitable openings in the plates. A similar switch operating lever 46 is pivotally mounted on the plate 20 by means of a pivot screw 47 and is provided with inturned fingers 48, 49 and 50. The fingers 48, 49 and 50, as best seen in Fig. 4, project into the path of travel of a 25¢ piece and thus are engaged by the coin in its travel about the rotor. The finger 45 as shown in Fig. 9 may project through the path of the 25¢ piece and into the path of the 10¢ piece so that it may be engaged by a coin of either denomination. The finger 44 preferably projects through the path of all three coins and is thus engaged by coins of any of the three denominations. The lever 42 has mounted thereon a roller 52 of insulating material adapted to engage one of the leaves of a switch 53 mounted on plate 20 and suitably insulated therefrom. The lever 46 carries a similar roller 54 engaging one of the leaves of a similar switch 55.

The coins received in the several compartments of the hopper 12 are guided thereby into the proper path leading into contact with the rotor discs 35, 37 or 39. The rotor is turned in the direction of the arrow in Fig. 3 by power means to be described hereinafter. As the coin strikes the finger 44, the frictional force exerted thereon by the rotor positively rolls the coin beneath the finger and thus forces the lever 42 outwardly. The roller 52 then engages the switch 53 and momentarily closes the same. In the case of a 25¢ or a 10¢ piece the operation is repeated when the coin strikes the finger 45. The position of a 25¢ piece at the instant of contact with the finger 45 is indicated at 56 in Fig. 3. Similarly, a 25¢ piece successively engages the fingers 48, 49 and 50 and produces three additional momentary closures of the switch 55.

In the operation just described, the frictional force exerted on the coin and tending to roll the same beneath the several fingers, exerts a wedging action which forces the fingers outwardly with a much greater force than could be applied by the weight or impact of a coin. The leaves of the switches 53 and 55 may therefore be made much stiffer than with gravity-operated switches and the moving parts may be correspondingly heavier and more durable. The increased stiffness of the leaves prevents vibration tendencies and reduces arcing at the contact tips, thus prolonging the life of said tips. As the same time the increased operating force available greatly increases the certainty of complete electric contact. The speed of operation may be controlled by controlling the speed of rotation of the rotor and even with relatively stiff and heavy switch construction may be much faster than with gravity operation.

The switches 53 and 55 are preferably connected in parallel in the circuit of the usual coin recording device and provide the usual successive actuations thereof. The recording device may be of a well known commercial form and forms no part of the present invention. For that reason it is not shown in the drawings nor described in detail.

The power mechanism for operating the rotor shaft 32 is shown in Figs. 2 and 4 and includes an electric motor 57 having a rotor shaft 58 which is journaled in side plates 59 and 60 secured to the plate 13 by suitable fastenings. The plates 59 and 60 serve as journals for the rotor shaft 32 and the latter is driven by the motor shaft 58 through a train of gears 61, 62, 63, 64, 65 and 66. The shaft 32 projects to the left of plate 59 as seen in Fig. 4 and carries a disc 67 having a spiral guideway 68 cut in the outer face thereof. A bracket 69 secured to the plate 13 by one of the bolts 28 supports a pivot pin 70 on which there is mounted an upwardly projecting lever 71. A compression spring 72 abuts against the inner face of said lever and against a cotter pin 73 mounted on the pivot pin 70. The lever 71 carries at its upper end a pin 74 engaging the spiral guideway 68. The spring 72 normally holds the lever 71 flush against the face of the bracket 69 in which position the pin 74 engages the guideway 68. The lever 71 may, however, be pressed backwardly against the pressure of the spring 72 to disengage the pin 74 from the guideway. A tension spring 75 secured to the lever 71 and to an anchorage 76 normally urges the lever 71 in the counterclockwise direction, referring to Fig. 2. An electric switch 77 is mounted on the plate 59 and suitably insulated therefrom and is connected in series with the windings 78 of the motor 57. One of the leaves of said switch carries an insulation piece 79 engageable by the lever 71.

The coin receiving slide 11 is provided with a pin 80 adapted to engage a lever 81 as the slide is pressed inwardly to deliver a coin to the hopper 12. The lever 81 is mounted on a horizontal shaft 82 which is journaled on suitable bearings. If more than one of the slides 11 are used, a corresponding pin 80 is mounted on each and a corresponding lever 81 is placed on the shaft 82 (see Fig. 10). The shaft 82 carries a cam 83 engageable with the upper end of a rod 84 slidably mounted in bearings 85 and 86. A compression spring 87 abutting against a washer 88 held in place by a pin 89 on the rod 84 normally urges said rod upwardly. The lower end of the rod 84 is engageable with a lever 90 mounted on a shaft 91 which is journaled on the wall 10 and on a bracket 92 secured to the bracket 69. The shaft 91 carries a member 93 having a flat surface 94 engageable with the inner face of the lever 71.

In the idle position of the apparatus just described, the lever 71 is in engagement with the block 79. The switch 77 is open and the motor 57 is idle. Upon the deposit of a coin the slide 11 is pressed inwardly, the pin 80 engages the pin 81 and the cam 83 forces the rod 84 downwardly. The downward pressure of the rod 84 on the lever 90 rocks the shaft 91 and tilts the face of the member 93 against the lever 71. Lever 71 is thus moved outwardly against the action of the spring 72 to free the pin 74 from the guideway 68. The spring 75 then draws the lever 71 inwardly to the position shown in Fig. 2 and 75

thus permits the switch 77 to be closed to start the motor. The action of the member 93 is only momentary so the pin 74 is immediately permitted to reenter the guideway 68. The movement of the pin 74 travelling in the guideway 68 as the disc 67 rotates, returns the lever 71 to its initial position. At the end of the return movement the lever strikes the block 79, opens switch 77 and stops the motor. The rotor thus makes several revolutions each time a coin is received in one of the slides 11 and is stopped at the end of a predetermined time after such receipt unless another coin is previously deposited. During the operation of the rotor the coin engages the same and is forced by the movement of the rotor to operate the appropriate switches 53 and 55, as previously described. The time of operation of the rotor is determined by the pitch of the spiral guideway 68 and is made sufficiently long for the coin to pass through any slug ejector which may be used between the slide 11 and hopper 12 and to complete its travel around the rotor and past the switches. If a second coin is received before a previous coin completes its operation, the mechanism operates to return the pin 74 to its inner position immediately and to start its outward travel again from that position. Thus ample time is provided for the complete travel of the last of several coins without interfering with the operation of coins previously received.

In order to prevent cheating by manipulation of the power supply the apparatus now to be described is provided. A bracket 100 is secured to the plate 59. A lever 101, the shape of which is best seen in Fig. 6, is pivotally mounted on said bracket by means of a vertical pivot screw 102. The lever 101 has an armature portion 103 extending into the space between the motor winding 78 and the pole pieces 104 of the motor. When said pole pieces are magnetized in the operation of the motor, the armature 103 is attracted toward said pole pieces and the lever 101 is moved about the pivot screw 102. A lever 105 is pivotally mounted on the lever 101 by means of a horizontal pivot screw 106 and thus has motion about both horizontal and vertical axes. The opposite end of lever 105 has secured thereto a tension spring 107 anchored to the plate 59. A pointed finger 108 is carried by the lever 105 and an insulation piece 109 is mounted on the opposite side of said lever and adapted to engage a leaf switch 110 which is mounted on and suitably insulated from the plate 59. The inner face of the disc 67 is provided with a plurality of grooves 111 arranged tangentially to a circle of slightly less than half the diameter of the disc 67 and engageable by the finger 108 on the lever 105.

Referring now to the wiring diagram Fig. 8, power for operating the device may be supplied through an attachment plug 112 having power lines 113 and 114 attached thereto and insertable in the usual wall receptacle not shown. The switch 77 and motor winding 78 are connected in series across the power lines and the motor, therefore, is operated whenever switch 77 is closed. The switch 110 is connected between power line 113 and the parallel connected switches 53 and 54, the opposite terminals of which are connected to a magnet coil 115 representing the coin register unit to be operated by the invention. The opposite terminal of said magnet is connected to power line 114. If it is desired to operate the motor 78 or magnet 115

on other than the 110 volts usually available, a suitable transformer may be included in the circuit in the usual manner.

In the operation of the portion of the apparatus just described, the mechanical parts are held in the position shown in Fig. 7 by the spring 107 as long as the motor is not in operation. In this position the finger 108 is located in rear of the disc 67 and is held out of contact with said disc. When a coin is received and the motor is energized, the armature 103 is attracted to the pole pieces 104 to rock levers 101 and 105 about pivot screws 102 and bring said finger into engagement with the rotating disc 67. The finger 108 enters one of the grooves 111 and is forced downwardly thereby, carrying the lever 105 about pivot screw 106 in opposition to spring 107. At the end of this downward movement the pin 109 has engaged and closed switch 110 and the finger 108 rides on the outer edge of disc 67, and continues to ride in that position as long as the motor operates. The time required for closure of switch 110 is much less than that required for the coin to reach the finger 44 so that the circuit for the coil 115 is in readiness for the operation of switch 53.

If the plug 112 is pulled while a coin is in engagement with one of the switch operating fingers, the motor is immediately deenergized and spring 107 returns the parts to the position of Fig. 7 in which switch 110 is open. When the plug 112 is reinserted in its socket, no circuit can be completed for the magnet 115 even though one of the switches 53 or 54 is closed. The pitch of the grooves 111 is so chosen that switch 110 can not again be closed until the motor has moved the coin to clear the switch operating finger and reopen the corresponding switch 53 or 54. The time delay in operation of switch 110 thus provided after the power supply has been reestablished makes cheating by manipulation of the power supply impossible. Other forms of time delay mechanisms are well known and may be employed for the purpose.

The foregoing specification describes the invention in one of its preferred forms, the details of which may be varied without departing from the scope of the invention as defined by the appended claims.

The invention claimed is:

1. In a coin controlled switch mechanism, a rotary member having a resilient outer face, guide means concentric with said rotary member and spaced therefrom to form an arcuate coin path with said rotary member, said path being slightly narrower than the diameter of a coin and the resilient face of said rotary member engaging an edge of said coin and yieldingly holding the same with its opposite edge pressed against said guide means, power means for rotating said rotary member to roll said coin through said path, and a switch operating member engageable by the coin in said rolling movement.

2. In a coin controlled switch mechanism, a rotary member, guide means constraining a coin to follow an arcuate path about said rotary member and with an edge of said coin in contact therewith, a motor for rotating said rotary member to roll a coin through said path, a switch operating member engageable by said coin in its rolling movement, a member having a spiral guideway rotatable with said rotary member, a follower engaging said guideway and movable by said engagement toward a normal idle position,

manually controlled means for moving said follower from said normal position to engage said guideway, a motor circuit, and a limit switch associated with said circuit and operated by said follower to start said motor when said follower is moved from its normal position and to stop said motor when said follower is returned to said normal position by engagement with said spiral guideway.

3. In a coin controlled switch unit for operating a coin registry device, a coin register circuit adapted to operate said registry unit each time current flow is established in said circuit, a coin operated switch in said circuit, motor operated means for moving a coin into and out of operative relation with said coin operated switch, a motor and motor circuit for operating said means, power lines supplying power for said register circuit and said motor circuit, a second switch controlling current flow in said register circuit, switch operating mechanism for said second switch movable by said motor from an initial position to a final position and operating said second switch to permit current flow in said register circuit in said final position only, and means controlled by current flow in said motor circuit adapted to return said mechanism to initial position each time current flow in said motor circuit ceases, the time required for said motor to move said mechanism from initial to final position being sufficient for said motor to move a coin which may have been in operative relation to said coin operated switch out of such relation, whereby cheating by opening and closing said power lines while a coin is in operative relation to said coin operated switch is prevented.

4. In a coin controlled switch mechanism, an annular rotatable member, an arcuate wall member concentric with said annular member and forming with said annular member a guide slot, one of said members being resilient and a switch operating member extending into said guide slot through said arcuate wall, said guide slot being of a width slightly less than the diameter of a coin of predetermined denomination, whereby said coin will be caused to roll throughout its travel in said guide slot while in engagement with both said wall and said annular member.

5. In a coin controlled switch mechanism, a rotary member, guide means constraining a coin to follow an arcuate path about said rotary member and with an edge of said coin in contact therewith, a motor for rotating said rotary member to roll a coin through said path, a switch operating member engageable by said coin in its rolling movement, manual means for starting said motor, a limit switch in the circuit of said motor, and means operable upon a predetermined number of revolutions of said rotary member to open said limit switch.

6. In a coin controlled switch mechanism, a rotary member, a guide arranged adjacent to said member and concentric therewith to constrain a coin to follow an arcuate path about said rotary member with an edge of said coin in contact therewith, a motor for rotating said rotary member, a switch operating member in the path of said coin, manual means for starting said motor, a limit switch in the circuit of said motor, a lever adapted to open said limit switch, and means operable upon a predetermined number of revolutions of said rotary member for moving said arm to switch opening position.
